Patented Jan. 14, 1969

213,239

FALSE EYELASH APPLICATOR

Marlene W. Flewwellin, 1025 Merner Road,
Hillsborough, Calif. 94010

Filed Nov. 13, 1967, Ser. No. 9,363

Term of patent 14 years

U.S. Cl. D86—10
Int. Cl. D28—03

Fig. 1.

Fig. 2.

Fig. 4.

Fig. 3.

FIG. 1 is a perspective view of a false eyelash applicator embodying my new design;

FIG. 2 is a side elevational view thereof;

FIG. 3 is a top plan view thereof; and

FIG. 4 is an end view thereof.

The side opposite that seen in FIG. 3 is a mirror image of the side shown.

I claim:

The ornamental design for a false eyelash applicator, substantially as shown and described.
